UNITED STATES PATENT OFFICE.

FRANKLIN A. ERRINGTON, OF NEW YORK, N. Y.

AUTOMATICALLY OPENING OR CLOSING DIE.

SPECIFICATION forming part of Letters Patent No. 642,811, dated January 30, 1900.

Application filed April 10, 1899. Serial No. 712,554. (No model.)

To all whom it may concern:

Be it known that I, FRANKLIN ALFRED ERRINGTON, a citizen of the United States, residing in New York city, borough of Richmond, (Stapleton P. O.,) State of New York, have invented certain new and useful Improvements in Automatically Opening or Closing Dies, of which the following is a specification.

My improvements relate to thread-cutting tools the dies of which are adapted to have sufficient axial and lateral movement independently of their supporting-body to close and open by coaction with the work or article upon which they cut threads; and the object of my invention is to provide a simple, practical, and efficient tool of the character described wherein when the work is pressed against the cutting-dies, or vice versa, they will close to the operative position, and when threads are cut upon the work and the axial movement of the work into the body is arrested the continued rotation of the dies or of the work will cause the dies to move outwardly axially of the supporting-body during operation, cutting their way along the work until the external thrust-faces of the dies thus automatically pass out of engagement with the internal thrust-faces of the supporting-body, whereupon said dies will automatically expand laterally of the supporting-body to permit the separation of the work and dies without stopping or changing the direction of rotation of the rotative member; and the invention consists in the novel details of improvement and the combinations of parts, that will be more fully hereinafter set forth and then pointed out in the claims.

Reference is to be had to the accompanying drawings, forming part hereof, wherein—

Figure 1 is an end view of a device embodying my invention, showing the parts in the open position, affording clearance between the dies for the removal of the work. Fig. 2 is a partly-sectional view on the line 2 2 in Fig. 1, the dies being shown in the closed or cutting position, half of the inner parts of the device being shown in full lines. Fig. 3 is a similar view, the dies being shown in the inoperative or open position. Fig. 4 is a side elevation of Fig. 1, the device being turned axially ninety degrees from the position shown

in Fig. 3. Fig. 5 is a vertical cross-section of Fig. 1 on the line 5 5, the dies being shown in the closed position.

Similar numerals of reference indicate corresponding parts in the several views.

1 indicates the supporting-body of the device, which is provided with a shank 3 for connection with either the turret or live spindle of a lathe or similar tool. Abutments 2 project from body 1, with openings 1^a between them, which afford ready egress for the escape of chips, &c. The body 1 is preferably internally and externally tapered at its abutments 2. To provide said body with laterally-adjustable internal thrust-faces, said tapered surfaces are shown connected by an elongated slot 2^a, through which screws 4^a pass to mesh with tapped holes in externally-tapered adjusting-blocks 4, by which means blocks 4 can be adjustably clamped to the internally-tapered faces 2^b of abutments 2. The planes of the externally-tapered surfaces 2^c of abutments 2 are preferably parallel with their respective internally-tapered surfaces 2^b and at right angles to the axis of their respective screws 4^a to permit the heads of said screws to bear evenly thereupon and to actuate blocks 4 laterally of body 1 when said screw-heads slide outwardly along the abutments 2. Set-screws 1^b are shown passing through the back plate 1^c of body 1 to engage the inner ends of adjusting-blocks 4 to lock said blocks from accidental inward movement axially of body 1 after the adjusting-screws 4^a have been tightened up. The shank 3 is shown hollow to receive an adjustable stop-piece 5, adapted to be rigidly connected with body 1 by a set-screw 5^a. This stop acts to limit the distance that work 6 can pass into the device. A die-holder 7 preferably surrounds the abutments 2 and is movable therealong independently of body 1, the heads of screws 4^a being accessible through openings 7^a, and the outward axial movement of die-holder 7 being preferably limited by the head of screws 4^a engaging the inner walls of openings 7^a. Alining-pieces 7^b project from the back of die-holder 7 along and overhang the body 1. The die-holder 7 is provided with a die-chamber 7^c, whose side walls are preferably indented by internal ways 7^d. A pair

of dies 8 9 are inserted through the axial bore 7^c of die-holder 7, said dies being preferably provided with external ways 8^d 9^d, that mesh with the internal ways 7^d of die-holder 7. After said dies are in place in die-holder 7 their inward movement along said die-holder is limited by removable abutments, (shown in the form of set-screws 7^f,) which prevent the accidental escape of dies 8 9 through axial bore 10 7^e of the die-holder.

The main object of my invention is to cause the dies 8 9 to contract or approach each other to the operative or cutting position and to expand or move away from each other to the 15 inoperative or open position to release the work. I provide means whereby this opening and closing of the dies can be effected by and during their movement axially of the body 1, and for this purpose I have shown 20 the body 1 as provided with internal thrust-faces 10 11, having associate cam-faces 12 13, the internal thrust-faces 10 being nearer together than the opposed internal thrust-faces 11, (see Figs. 2 and 3,) or, in other words, the 25 planes of the inner internal thrust-faces 10 are within the planes of the outer internal thrust-faces 11. Thus the opposed internal thrust-faces 10 11 and their associate cam-faces 12 13 provide a die-chamber 1^a 7^c, di- 30 vided into sections or portions of different diameters, the outer portion of said chamber being of greater diameter than the inner portion thereof. I preferably form the faces 10 11 12 13 upon adjusting-blocks 4 instead of 35 integral with body 1, (see Fig. 2,) as it is desirable that said opposed faces be adjustable toward and from each other independently of said body, and to enable the blocks 4 to move axially and laterally of body 1 in uni- 40 son I provide each of said blocks with a laterally-projecting lug 4^b, said lugs being adapted to engage the inner face of die-holder 7 simultaneously, so that upon the screws 4^a 1^b being slackened back and the die-holder 7 45 moved inwardly along body 1 against lugs 4^b the blocks 4 will be moved inwardly axially of body 1 by said die-holder and laterally of said body by the internal tapered faces 2^b of the abutments 2. When the desired adjust- 50 ment is attained, the adjusting-screws 4^a are then tightened up and the set-screws 1^b brought against the inner ends of blocks 4.

By means of the lateral adjustment of the adjusting-blocks 4 the cutting diameter of 55 the dies can be adjusted within certain limits and the adjustment of the stop 5 determines the length of the thread cut upon the work, although this length may be varied by other means that arrest the advance of the work 60 into the device.

The dies 8 9 are to bear against the opposed internal thrust-faces 10 11 of the die-chamber 1^a 7^c when the dies are in the closed or working position, (see Fig. 2,) and to cause 65 the dies 8 9 to move laterally of the die-chamber 1^a 7^c during their axial movement therein I have shown said dies as provided at their

inner ends with cutting-faces and at their opposite ends with external thrust-faces 14 15, preferably lying in different planes, the 70 planes of the inner external thrust-faces 14 being within the planes of the outer external thrust-faces 15 to enable the die thrust-faces 14 15 to bear simultaneously upon the internal body thrust-faces 10 11 during operation, 75 and at the inner ends of external thrust-faces 14 of the dies I have preferably provided cam-faces 17 to coact with the cam-faces 13 of the blocks 4, and between the external thrust-faces 14 15 of the dies I have provided cam-faces 16 to coact with the body cam-faces 12 carried by blocks 4. It is obvious that in providing both the blocks and the dies with coacting cam-faces that are correspondingly beveled I do so to secure a more permanent 80 set of cam-faces; but only one of said sets of cam-faces, as 12 13, need be beveled, and the external thrust-faces 14 15 could terminate in straight edges and still coact with the cam-faces 12 13 to move the dies 8 9 laterally. 90 When the dies 8 9 are pushed inward axially of the body 1, said dies will slide laterally and axially of said body independently of (or along) the internal body cam-faces 12 13 and thrust-faces 10 and 11 until the thrust-faces 95 14 15 of said dies will respectively oppose the internal body thrust-faces 10 11 of the blocks 4, as shown in Fig. 2, and said dies will be in their closed or working position to cut threads on work 6. From this it will be seen that each 100 of the dies 8 9 has two external thrust-faces, which keep the die in proper alignment and prevent tilting of the die while moving independently axially of its supporting-body. When the dies are moved outward axially of body 1, said dies will slide axially and laterally of said body independently of (or along) the internal body thrust-faces 10 and 11 until their inner external thrust-faces 14 will oppose the outer internal thrust-faces 11 of 110 blocks 4, (see Fig. 3,) and as the distance between the outer internal thrust-faces 11 is greater than between the inner internal thrust-faces 10 the dies will expand or move apart instead of continuing to cut threads in 115 work 6 and the work 6 can be withdrawn. (See Fig. 1.) The beveled faces or cams 12 13 coact with the cam-faces 16 17 to move the dies 8 9 laterally toward each other when said dies are moved axially inwardly of the die-chamber. The arrangement is such that when the dies are in the position shown in 120 Fig. 3 and they are next pressed against the work, or vice versa, the cam-faces of dies 8 9 and blocks 4 will move said dies laterally toward each other to the working position 125 (shown in Fig. 2,) whereupon threads will be cut upon work 6 as the dies or the work rotate. When the work 6 reaches the stop 5, its axial movement into the device will be arrested and the continued rotation of the device (or work) will cause the dies to coact 130 with the threads already cut upon the work 6 to move said dies axially of the supporting-

body 1 during operation independently of the internal body thrust-faces and continue cutting threads in the work while moving outwardly until the external thrust-faces 14 15 of the dies pass out of engagement with the internal body thrust-faces 10 11 of the blocks 4, whereupon the dies will expand laterally of body 1 automatically and the work can be withdrawn without stopping the rotation of the moving member or reversing the direction of rotation thereof.

A distinctive functional effect of employing independent (not integral with each other) dies that are movable both laterally and axially independently of the supporting-body 15 is that when the device is stationary and the work rotates I may utilize gravity to assist in closing the dies, as it is apparent that when the device is in the position shown in Fig. 1 20 the upper die will drop sufficiently to engage the advancing work to be threaded, in which case the bottom die only will require a cam to raise it over the shoulder or shoulders 12 13 as the pressure of the advancing work 25 against the upper die pushes the dies axially of the body from the outer to the inner portion of the die-chamber. However, when the device is rotated and the work is held from rotation it is preferable to provide a cam 30 for each die to move it positively laterally of body 1. By preference, I form the faces 14 15 16 17 of the dies 8 9 upon die-blocks 18, which are shown detachably connected with the dies, for which purpose I have shown 35 screws 18^a passing through apertures in said blocks and meshing with threads in tapped holes in the dies 8 9. (See Figs. 1, 2, and 3.) The die-blocks 18 are each shown provided with an indenture to receive the central projection or external way 8^d or 9^d, as the case may be, of the die 8 or 9 to prevent the independent rotation of the die-block upon the die, and thereby loosening the screws 18^a. The screws 18^a can be loosened and the dies 40 45 8 9 reversed thereupon when the outer cutting-teeth become worn, so that the inner teeth can become the outer ones.

Having now described my invention, what I claim is—

50 1. The combination with a supporting-body provided with internal thrust-faces, of a die-holder connected with said body to rotate in unison therewith and movable axially thereof, and a plurality of independent dies movable along said die-holder laterally of said body and provided at their ends opposite their cutting-faces with external thrust-faces that bear against said internal thrust-faces during operation, said dies being movable 55 60 with said die-holder axially of said body during operation independently of said internal thrust-faces, substantially as described.

65 2. The combination with a supporting-body provided with internal thrust-faces, of a die-holder connected with said body to rotate in unison therewith and movable axially thereof, and a plurality of independent dies mov-

able along said die-holder laterally of said body and provided at their ends opposite their cutting-faces with external thrust-faces 70 that bear against said internal thrust-faces during operation, said dies being movable with said die-holder axially of said body during operation independently of said internal thrust-faces, and one of said thrust-faces being provided with an associate cam-face to move one of said dies laterally of said body during the inward movement of said dies axially thereof, substantially as described.

3. The combination with a supporting-body 80 provided with internal thrust-faces, of a die-holder connected with said body to rotate in unison therewith and movable axially thereof, and a plurality of independent dies movable along said die-holder laterally of said body and provided at their ends opposite their cutting-faces with external thrust-faces that bear against said internal thrust-faces during operation, said dies being movable with said die-holder axially of said body during operation independently of said internal thrust-faces, and means to aline said die-holder with the axis of said body, substantially as described.

4. The combination with a supporting-body 95 provided with internal thrust-faces, of a plurality of independent dies connected with said body to rotate in unison therewith and movable laterally thereof and provided at their ends opposite their cutting-faces with external thrust-faces that bear against said internal thrust-faces during operation, said dies being movable axially of said body during operation independently of said internal thrust-faces, each of said dies having a projection, and a die-holder movable axially of said body and provided with an indenture that meshes with said projections of said dies to connect said dies to move in unison with said die-holder axially of said body and independently of each other along said die-holder laterally of said body, substantially as described.

5. The combination with a supporting-body having abutments with an opening therebetween, said abutments having their opposed surfaces provided with internal thrust-faces, of a plurality of dies situated between said abutments and connected with said body to rotate in unison therewith and movable laterally thereof and provided at their ends opposite their cutting-faces with external thrust-faces that bear against said internal thrust-faces during operation, said dies being movable axially of said body during operation independently of said internal thrust-faces, substantially as described.

6. The combination with a supporting-body having abutments with an opening therebetween, said abutments having their opposed surfaces provided with internal thrust-faces, a die-holder surrounding said body and movable axially thereof, and a plurality of dies situated between said abutments and mov-

able along said die-holder laterally of said body and provided at their ends opposite their cutting-faces with external thrust-faces that bear against said internal thrust-faces during operation, said dies being movable with said die-holder axially of said body during operation independently of said internal thrust-faces, substantially as described.

7. The combination with an internally-tapered supporting-body provided with externally-tapered adjusting-blocks adjustably connected therewith and having internal thrust-faces, of a plurality of dies connected with said body to rotate in unison therewith and movable laterally thereof and provided at their ends opposite their cutting-faces with external thrust-faces that bear against said internal thrust-faces during operation, said dies being movable axially of said body during operation independently of said internal thrust-faces, substantially as described.

8. The combination with an internally-tapered supporting-body provided with externally-tapered adjusting-blocks adjustably connected therewith and having internal thrust-faces, of a plurality of dies connected with said body to rotate in unison therewith and movable laterally thereof and provided at their ends opposite their cutting-faces with external thrust-faces that bear against said internal thrust-faces during operation, said dies being movable axially of said body during operation independently of said internal thrust-faces, and one of said thrust-faces being provided with an associate cam-face to move one of said dies laterally of said body during the inward movement of said dies axially thereof, substantially as described.

9. The combination with an internally-tapered supporting-body provided with externally-tapered adjusting-blocks having internal thrust-faces, means to adjust said blocks axially and laterally of said body in unison and means to hold said blocks in position when adjusted, of a plurality of dies connected with said body to rotate in unison therewith and movable laterally thereof and provided at their ends opposite their cutting-faces with external thrust-faces that bear against said internal thrust-faces during operation, said dies being movable axially of said body during operation independently of said internal thrust-faces, substantially as described.

10. The combination with a supporting-body provided with adjusting-blocks having internal thrust-faces, of a die-holder connected with said body to rotate in unison therewith and movable axially thereof, said die-holder and blocks having abutting members to adjust said blocks relatively to each other laterally of said body in unison, and a plurality of dies movable along said die-holder laterally of said body and provided at their ends opposite their cutting-faces with external thrust-faces, said dies being movable with said die-holder axially of said body during op-

eration independently of said internal thrust-faces, substantially as described.

11. The combination with a supporting-body 70 provided with internal thrust-faces, of a plurality of dies connected with said body to rotate in unison therewith and movable laterally thereof and provided at their ends opposite their cutting-faces with external thrust-faces that bear against said internal thrust-faces during operation, said dies being movable axially of said body during operation independently of said internal thrust-faces, and an adjustable abutment rigidly carried by 80 said body to limit the inward movement of said dies axially of said body, substantially as described.

12. The combination with an internally-tapered supporting-body provided with externally-tapered adjusting-blocks having internal thrust-faces, said body being provided with set-screws adapted to engage the inner ends of said blocks to lock them from inward movement axially of said body, of a plurality 90 of dies connected with said body to rotate in unison therewith and movable laterally thereof and provided at their ends opposite their cutting-faces with external thrust-faces that bear against said internal thrust-faces during 95 operation, said dies being movable axially of said body during operation independently of said internal thrust-faces, substantially as described.

13. The combination with a body provided 100 with internal thrust-faces, of a plurality of independent dies connected with said body to rotate in unison therewith and movable laterally thereof and provided at their ends opposite their cutting-faces with external thrust-faces that bear against said internal thrust-faces during operation, said dies being movable axially of said body during operation independently of said internal thrust-faces, and means to limit the inward movement of said 110 dies laterally of said body, substantially as described.

14. The combination with a body provided with internal thrust-faces of a die-holder connected with said body to rotate in unison 115 therewith and movable axially thereof, and a plurality of independent dies movable along said die-holder laterally of said body and provided at their ends opposite their cutting-faces with external thrust-faces, said dies being movable with said die-holder axially of said body during operation independently of said internal thrust-faces, said die-holder being provided with an abutment to limit the inward movement of said dies laterally of said 120 body, substantially as described.

15. The combination with a body provided with internal thrust-faces, of a die-holder connected with said body to rotate in unison therewith and movable axially thereof, and a plurality of independent dies movable along 130 said die-holder laterally of said body and provided at their ends opposite their cutting-faces with external thrust-faces, said dies be-

ing movable with said die-holder axially of said body during operation independently of said internal thrust-faces said die-holder having a die-chamber provided at its mid-portion with an enlarged entrance, said dies being adapted to be inserted at said entrance and guided along the narrower side portions of

said chamber, and means to retain said dies in said narrower side portions of said chamber, substantially as described.
